UNITED STATES PATENT OFFICE.

LOUIS JOHN LE MESURIER, OF BELMONT, ENGLAND.

APPARATUS FOR STORING FLUID UNDER PRESSURE.

Application filed July 20, 1925, Serial No 44,953, and in Great Britain December 30, 1924.

This invention relates to apparatus for storing fluid under pressure and has for its main object the provision of an improved form of apparatus for storing fluid at high pressure or at two or more different pressures.

A further object is to provide a durable and reliable apparatus for storing fluid, such as air, under pressure, which apparatus is less expensive to install than the devices now in common use.

A further object is to provide an apparatus of the above described character which greatly conserves the space necessary for installations of this character.

A further object is to provide in a device for storing fluid at high pressure or at two or more different pressures, an automatic pressure regulation whereby the stored fluid is maintained at a constant predetermined pressure in the apparatus and whereby a constant predetermined difference may be maintained between the fluids stored at different pressures, to prevent the difference between the high and low pressures from exceeding a predetermined limit. Other objects will be in part obvious and in part pointed out hereinafter.

According to the present invention, one or more reservoirs adapted to contain fluid at a relatively high pressure are disposed partially or wholly within a reservoir adapted to contain fluid at a relatively low pressure. In this way the walls of each high pressure reservoir which lie within the low pressure reservoir are subjected only to the difference of fluid pressure between the two reservoirs and thus need not be of such strength as has hitherto been necessary. Thus, where it has previously been necessary to make high pressure fluid reservoirs in the form of solid forged or drawn steel bottles, it may be sufficient with apparatus according to this invention to build them up from steel or other metal plates in a manner previously employed only for relatively low pressure reservoirs.

The invention is particularly applicable to apparatus for storing fluid at two or more different pressures in which all the reservoirs contain the same fluid, for example compressed air, for use in the starting and operation of the engines of a motor ship. In such apparatus an automatic pressure reducing valve may be provided between the high and low pressure reservoirs so as to prevent the difference between the high and low pres-

sures exceeding a predetermined limit and so as to maintain a substantially constant difference between these pressures. This valve is conveniently disposed outside the low pressure reservoir and connected thereto and to the high pressure reservoir by suitable pipes or the like so as to facilitate inspection and adjustment of the valve. A similar arrangement may also be employed where different fluids are contained in the two reservoirs, the pressure reducing valve in this case being adapted to open only in case of emergency, so as to act as a safety valve, and not being operative for slight pressure variations such as might occur in the normal working of the apparatus. In either case either or both of the high and low pressure reservoirs may be provided with a safety valve adapted to open so as to permit escape of fluid to the atmosphere when the pressure therein exceeds a predetermined limit.

Where a relief valve between the two reservoirs is employed, this valve is conveniently so set that when the maximum pressure difference between the two reservoirs is exceeded the valve will lift and allow fluid to pass from the inner to the outer reservoir. Thus, when charging, assuming both reservoirs to be empty, the compressor or the like will deliver fluid to the inner reservoir until the pressure therein reaches the same value as the maximum pressure difference at which the two reservoirs are designed to operate. The relief valve will then open so as to deliver the surplus fluid into the outer reservoir so that the pressures in the two reservoirs will then rise simultaneously while maintaining a constant pressure difference between them. Similarly, when discharging from the outer reservoir the same pressure difference will be maintained since when the pressure in the outer reservoir drops due to fluid being drawn off therefrom the relief valve between the two reservoirs will open and permit some of the fluid to escape from the inner reservoir to the outer reservoir until the desired pressure difference is again established.

Alternatively, or in addition to a relief valve between the two reservoirs, a valve may be provided adapted to establish communication between the reservoirs when the pressure in the low pressure reservoir drops below a certain predetermined value. With this arrangement, supposing both the reservoirs to be empty, the valve will be open and when compressed fluid is delivered it will thus pass

freely to both reservoirs until the fluid in the outer reservoir reaches the predetermined pressure for which the valve is set. As soon as this pressure is exceeded the valve will close and thereafter fluid will only be delivered to the inner reservoir until its maximum working pressure is reached. The predetermined pressure for the outer reservoir at which the communicating valve closes is conveniently the maximum pressure under which this reservoir is intended to work.

With this arrangement, when discharging from the low pressure reservoir, as soon as any fluid is drawn off, the pressure in the low pressure reservoir drops below the predetermined value and the communicating valve opens to admit fluid from the high pressure reservoir until the predetermined pressure is again established in the low pressure reservoir. This sequence of operation continues until if no more fluid is delivered to the high pressure reservoir the pressure in the high pressure reservoir has dropped to the same pressure as the low pressure reservoir, when, there being no more high pressure fluid to bring the pressure in the low pressure reservoir up to the predetermined pressure, the pressure in the low pressure reservoir remains below such predetermined pressure and the communicating valve thus remains open, so that fluid is drawn off from both reservoirs simultaneously until all the fluid in both reservoirs is exhausted.

The communicating valve may be controlled by a spring-controlled diaphragm or the like subjected to the pressure in the low pressure reservoir. With such an arrangement, however, if, as is preferable, a valve of comparatively large size is employed, the action of the high pressure fluid on one side thereof will appreciable affect the pressure at which it opens. To avoid this the valve is conveniently not directly controlled by the pressure in the low pressure reservoir but is connected to a piston adapted to be acted upon by high pressure fluid delivered through a subsidiary relay valve which is of relatively small size and is connected to a spring-controlled diaphragm or the like subjected to the pressure in the low pressure reservoir. One side of the piston controlling the main valve is conveniently subjected to the pressure in the low pressure reservoir, a small leak being provided through the piston whereby when the high pressure fluid ceases to be delivered, behind the piston by the relay valve, the pressure on the two sides of the piston will automatically become equal and the valve controlled thereby will be closed by a spring or the like.

The invention may be applied to apparatus in which fluid is stored at more than two pressures, and in this case the reservoirs may be arranged one inside the other, the innermost reservoir being adapted to contain the

fluid at the highest pressure while the outermost reservoir is adapted for the fluid at the lowest pressure.

The invention may be carried out in the various ways but one construction of apparatus according to the present invention suitable for storing compressed air for use in the starting and operation of the engines of a motor ship is illustrated diagrammatically by way of example in the accompanying drawings, in which

Figure 1 is a sectional side elevation of apparatus employing one system of relief valves,

Figure 2 is a front elevation partly in section of the apparatus shown in Figure 1, and

Figure 3 is a diagrammatic view of an alternative system of relief valves which may be employed.

In the construction illustrated in Figures 1 and 3 the low pressure reservoir is in the form of a cylindrical shell 10 built up from a series of steel plates and closed at its ends by suitable curved end caps 11 and 12. Supported eccentrically within the low pressure reservoir by means of lugs 13 and bolts 14 is a high pressure reservoir 15 which is built up from metal plates in a similar manner to the low pressure reservoir 10 and is of such dimensions as to leave the desired space for the low pressure air between its walls and those of the low pressure reservoir 10. Provided in the ends of the high and low pressure reservoir are respectively man holes 16 and 17.

Mounted in the end 11 of the low pressure reservoir 10 is a union 18 one branch 20 of which leads through the low pressure reservoir into the high pressure reservoir while the other branches are connected respectively to a pipe 21 through which compressed air is supplied from the compressor or the like and to a pipe 22 leading to the high pressure side of a pressure reducing valve 23. The relief side of the pressure reducing valve 23 is connected through a pipe 24 to the high pressure side of a second relief valve 25 which also communicates through a pipe 26 with the low pressure reservoir 10.

It will thus be seen that the valve 23 will open if and when the difference in pressure between the high and low pressure reservoirs reaches or exceeds a predetermined limit so as to permit some of the air in the high pressure reservoir to escape into the low pressure reservoir while, if the pressure in the low pressure reservoir exceeds a predetermined limit, the relief valve 25 will open and permit escape of the surplus fluid to the atmosphere.

Thus the low pressure reservoir is automatically supplied with air through the valve 23 and is maintained at the correct pressure relatively to the pressure in the high pressure reservoir. High pressure air may be

drawn off through the pipe 21 while low pressure air can be drawn off through a pipe or outlet 27 connected to the pipe 24.

The pipe 20 is preferably bent substantially as shown in the drawings so as to allow a certain degree of flexibility between the high and low pressure reservoirs and allow a clear passage between the two man holes 16 and 17.

10 In the system of relief valves diagrammatically illustrated in Figure 2 a relief valve 28 controlled by a spring 30 is adapted to be opened by air pressure admitted from the high pressure reservoir 15 behind a piston 31 disposed in a cylinder 32. The valve when opened permits air to pass from a pipe or housing 33 communicating with the high pressure reservoir to a pipe 34 communicating with the low pressure reservoir. The de-

20 livery of high pressure air behind the piston 31 is controlled by a relay valve 35 which is controlled jointly by springs 36, 37, and a diaphragm 38 joined to valve 35, and arranged in a housing 40 open to the atmosphere through port 41, the diaphragm being thus subjected to the pressure in the low pressure reservoir. The arrangement is such that, when the air in the low pressure reservoir drops below a certain predetermined pres-

30 sure the relay valve 35 opens and admits high pressure air to a pipe 42 communicating with the back of the piston 31. The piston 41 is thus moved to open the main valve 28 so as to admit air from the high to the low pressure reservoir. The piston 31 is provided with a small leak 43 so that when the relay valve 35 closes due to the pressure in the low pressure reservoir again reaching the predetermined value, the high pressure air will

40 pass through the piston 31 and permit this piston to move so as to close the main valve 28. In addition to the relay valve 35 a relief valve 44 the sides of which are subjected respectively to the high and low pressures

45 may be provided adapted to open so as to admit high pressure air behind the piston 31 through the pipe 42 and thus open the valve 28 if the difference in pressure in the two reservoirs exceeds a predetermined value.

50 With the arrangement shown in Figure 3, it will be seen that whenever the pressure in the low pressure reservoir drops below the predetermined value, the relay valve 35 will open and thus bring about the opening

55 of the main valve 28. This permits high pressure air to flow into the low pressure reservoir until the predetermined pressure is again built up, when the relay valve and main valves will automatically close. Fur-

60 ther, when the pressure in the high pressure reservoir is below the predetermined pressure for the low pressure reservoir, the valves 35 and 28 will be permanently open so that all the air can be drawn from both reservoirs

65 without providing a special delivery pipe

from the high pressure reservoir. Further, when charging as through pipe 45, it enables both reservoirs to be charged simultaneously until the predetermined pressure is reached and only after this is the additional pressure built up in the high pressure reservoir. An additional advantage of this system is that the relay valve 35 is more sensitive than would be a large relief valve controlled only by a spring thus ensuring that the main relief valve 28 will be opened at the correct pressure.

70 Instead of the high pressure reservoir being disposed wholly within the low pressure reservoir the two reservoirs may have a common end (not shown) made of such strength as to withstand the higher pressure, the high pressure reservoir being only partly within the low pressure reservoir in this construction. Further, more than one high pressure reservoir may be disposed within the low pressure reservoir or the air or other fluid may be stored at more than two pressures the reservoirs being arranged one inside the other with the centre one containing the fluid at the highest pressure and the outside one containing the fluid at the lowest pressure.

75 The invention may be applied to apparatus in which only high pressure or only low pressure air or other fluid is required or where fluid of both pressures is employed. Where only low pressure fluid is required this invention enables the space necessary to accommodate storage reservoirs to be reduced, since the high pressure reservoir is disposed within the low pressure reservoir. Further, it permits high pressure fluid to be drawn off direct if required. Where only high pressure fluid is required it enables the reservoirs to be built up of steel or other metal plates 80 and to be of much larger size and more cheaply produced than is possible with the forged or drawn steel air bottles hitherto employed, since the walls of the high pressure reservoir have only to be of sufficient strength to withstand the difference between the pressures of the fluid in the two reservoirs.

100 It is to be understood that, although the invention has been particularly described with reference to apparatus for storing air for use in the starting and operation of the engines of a motor ship, it may be employed for other purposes and for storing under pressure fluids other than air, the details of construction being varied to suit the purpose 105 for which the apparatus is intended.

I claim:

1. In apparatus for storing fluid under pressure, in combination with a reservoir adapted to contain fluid under pressure a 115 reservoir disposed within the first reservoir and subjected to the pressure of the fluid therein and adapted to contain fluid at a higher pressure than that in the first reservoir, and a connection between said reser- 120

125

voirs including a main valve, a piston controlling said valve, and means operable to admit fluid at the pressure of the second reservoir behind the piston to thereby open the main valve upon decrease of pressure in the first reservoir.

2. In apparatus for storing fluid under pressure, in combination with a reservoir adapted to contain fluid under pressure, a reservoir disposed within the first reservoir and subjected to the pressure of the fluid therein and adapted to contain fluid at a higher pressure than that in the first reservoir, a connection between said reservoirs including a main valve, and a relay valve controlled by a diaphragm or the like and operable upon lowering of the pressure in the first reservoir to admit fluid at the pressure of the second reservoir to said piston to thereby open said main valve.

3. In apparatus for storing fluid under pressure, in combination with a reservoir adapted to contain fluid under pressure, a reservoir disposed within the first reservoir and subjected to the pressure of the fluid therein and adapted to contain fluid at a higher pressure than that in the first reservoir, a spring controlled piston normally subjected to the pressure of the first reservoir, a leak thru said piston, and a relay valve controlled by a diaphragm or the like and operable upon lowering of the pressure in said first reservoir to admit fluid at the pressure of the second reservoir to said piston to open said main valve, said leak permitting the high pressure fluid to pass thru said piston and the main valve to close under the action of its spring upon closing of said relay valve.

4. In apparatus for storing fluid under pressure, in combination with a reservoir adapted to contain fluid under pressure, a reservoir disposed within the first reservoir and subjected to the pressure of the fluid therein and adapted to contain fluid at a higher pressure than that in the first reservoir, and a connection between said reservoirs including a main valve, a piston controlling said valve, means operable to admit fluid at the pressure of the second reservoir behind the piston to thereby open the main valve upon decrease of pressure in the first reservoir, and a relief valve operable upon an increase of the pressure differential between said reservoirs to admit the high pressure fluid to the piston to thereby open said main valve between said reservoirs.

5. In an apparatus for storing fluid under pressure, the combination with a reservoir

adapted to contain fluid under pressure, of a reservoir disposed within the first named reservoir and adapted to contain fluid at a higher pressure than that in the first named reservoir, whereby the inner reservoir is subjected to the pressure of the fluid in the outer reservoir thereby to partially counter-balance the pressure of the fluid contained therein, a connection between said reservoirs including an automatic pressure reducing valve and a piston controlled relief valve, said relief valve adapted to admit high pressure fluid behind the piston of the relief valve when the difference in pressure in the two reservoirs equals or exceeds a predetermined amount.

6. In an apparatus for storing fluid under pressure, the combination with a reservoir adapted to contain fluid under pressure, of a reservoir disposed within the first named reservoir and adapted to contain fluid at a higher pressure than that in the first named reservoir, whereby the inner reservoir is subjected to the pressure of the fluid in the outer reservoir thereby to partially counter-balance the pressure of the fluid contained therein, the lower pressure reservoir being provided with an automatic relief valve adapted to permit the escape of fluid if the pressure therein exceed a predetermined limit.

7. In an apparatus for storing fluid under pressure, the combination with a reservoir adapted to contain fluid under pressure, of a reservoir disposed within the first named reservoir and adapted to contain fluid at a higher pressure than that in the first named reservoir, whereby the inner reservoir is subjected to the pressure of the fluid in the outer reservoir thereby to partially counter-balance the pressure of the fluid contained therein, a connection between said reservoirs operable to establish communication therebetween, and means to maintain a constant pressure differential between the reservoirs.

8. In an apparatus for storing fluid under pressure, the combination with a reservoir adapted to contain fluid under pressure, of a reservoir disposed within the first named reservoir and adapted to contain fluid at a higher pressure than that in the first named reservoir, whereby the inner reservoir is subjected to the pressure of the fluid in the outer reservoir thereby to partially counter-balance the pressure of the fluid contained therein, and automatic means to maintain a constant pressure differential between said reservoirs.

Signed at New York, New York, this 27th day of June, 1925.
